CLAIM

The ornamental design for a tray for holding vessels, as shown and described.

DESCRIPTION

FIG. 1 is a top perspective view of a tray for holding vessels in an open configuration;

FIG. 2 is a left side elevation view thereof in an open configuration;

FIG. 3 is a right side elevation view thereof in an open configuration;

FIG. 4 is a front elevation view thereof in an open configuration;

FIG. 5 is a back elevation view thereof in an open configuration;

FIG. 6 is a top plan view thereof in an open configuration;

FIG. 7 is a bottom plan view thereof in an open configuration; and,

FIG. 8 is a top perspective view thereof in a closed configuration.

The broken lines, the areas within them, and the areas bounded by both broken lines and solid lines depict portions of the Tray for Holding Vessels that form no part of the claimed design.

The dot dash dot broken lines depict the boundaries of the claim and form no part thereof.

1 Claim, 6 Drawing Sheets
